CLAIM

The ornamental design for an industrial camera as shown and described.

DESCRIPTION

FIG. 1 is a front perspective view of an industrial camera. FIG. 2 is a back perspective view of the industrial camera shown in FIG. 1.

FIG. 3 is a right view of the industrial camera shown in FIG. 1.

FIG. 4 is a left view of the industrial camera shown in FIG. 1.

FIG. 5 is a front view of the industrial camera shown in FIG. 1.

FIG. 6 is a back view of the industrial camera shown in FIG. 1.

FIG. 7 is a top view of the industrial camera shown in FIG. 1; and,

FIG. 8 is a bottom view of the industrial camera shown in FIG. 1.

The broken lines shown in the drawings represent portions of the industrial camera that form no part of the claimed design.
